UNITED STATES PATENT OFFICE.

OTTO STRUFE, OF DWIGHT, ILLINOIS.

REFRIGERATOR.

Application filed April 12, 1926. Serial No. 101,230.

These improvements relate to refrigerators adapted to accommodate ice in the form of substantially large chunks or pieces for extracting heat units from the hollow 5 interior of the device. They have a relation further to that class of ice refrigerators adapted for what is known as "outside icing".

According to the outside-icing method of refrigeration the practice has been to install 10 within the kitchen, pantry or whatever the inside room may be, an ice box or refrigerator having two doors opening into the ice compartment, one at the front of the device and the other at the back, cutting a hole 15 through the wall of the building of about the size of the rear door, putting a wooden casing in that opening, and hinging an ordinary wooden door on the outside of the building to cover that opening, the refrigerator being 20 finally positioned so that the rear door thereof is in alignment with the wall opening. In such case the iceman may fill the ice 25 chamber of the refrigerator by first opening the door outside the building and then opening the rear door of the refrigerator, thus opening a passageway to the interior of the ice chamber.

While the method of filling such refrigerators from the outside of the building has 30 many advantages over the practice, also very common, of carrying the ice into the room and inserting it through the front doorway of the refrigerator, many serious objections obtain in the outside-icing practice. One of 35 these is in the fact that the doors closing the ice chamber are necessarily thick, usually several inches through, since they contain 40 heat insulating material such as cork for protecting the refrigerator opening against the entrance of heat units from the outside. The arrangement of the rear door is such that when it swings into the passageway leading through the wall of the building it necessarily occupies so much of that space 45 as to limit the size of the piece of ice which may be passed through the rear doorway of the ice box. To get such a door out of the way it would be necessary to swing it substantially parallel to the rear surface of the 50 ice box, which swinging is of course impossible owing to the presence of the building wall. Another objection is in the fact that the materials forming the passageway to the hollow interior of the ice box soon become 55 saturated with water and accumulate dirt, give rise to the presence of vegetable growths,

cause the passageway materials and the wall generally to rot, smell foul, and be generally unsanitary, and, in addition, leakage of water takes place between the inner surface 60 of the building wall and the refrigerator, causing the plaster if present to become loose and fall away or to become saturated and foul, and thus generally, in all circumstances, producing an unsanitary condition at a place 65 impossible to clean and remedy without removing the ice box or refrigerator as a whole or even the casing for the ice passageway.

The present improvements have for some 70 of their objects the overcoming of all of the disadvantages and objections mentioned or indicated as inhering in the current means and method of outside icing as hereinabove set forth. The improvements have further 75 important objects in such provisions as an increased ice capacity for a given size of refrigerator, meaning one which occupies a given space in the room, which increased capacity and the arrangement of the space 80 results in the provision of means for receiving a greater quantity of ice in a single piece of standard shape and size, say weighing one hundred pounds, the larger piece having a proportionately longer life in the refrigerator than the same weight in smaller units, 85 whereby such relatively small refrigerator may be iced to last several days whereas otherwise daily icing would be required, and resulting further in a more equal maintenance of a low temperature in the refrigerator, and, for the most part, a lower temperature, than will be had where the icing 90 is done with smaller units.

A further object is to provide one feature 95 of these improvements in the form of an attachment to any ordinary ice refrigerator whereby such refrigerator may be made to accommodate, as one advantage, a very much larger amount of ice, and to accommodate, as another and important advantage, and 100 which may be had substantially regardless of the internal dimensions of the ice chamber, cakes of ice in standard sizes. Thus an ordinary refrigerator having, we will say, a relatively small ice compartment of 105 dimensions which do not contemplate any particular standard size of commercial ice, may be transformed according to these improvements into a device which will accommodate a one-hundred-pound cake, thus saving much expense to the ice merchant who makes the deliveries, much inconvenience as 110

well as expense to the owner of the refrigerator, and, withal, providing better results in refrigeration.

Other objects and advantages will appear 5 hereinafter.

In the drawings Figure 1 is a fragmentary perspective in front, top and side view of a refrigerator according to these improvements; Fig. 2 is a horizontal section as on 10 the line 2—2 of Fig. 1; and Fig. 3 is a vertical section as on the line 3—3 of Fig. 1.

The fundamental refrigerator structure illustrated comprises a main body having a top wall 9, vertical side walls 10, a rear wall 11 (Fig. 3), a front wall which will be denominated in general 12, and a bottom wall 13 (Fig. 3). The front wall is ordinarily provided with several doors opening into various compartments. In the drawings the door 12^a opens into the ice compartment 14 while the door 12^b provides entrance to a compartment more particularly adapted for food or other objects and is usually provided with shelves.

With respect to the main refrigerator body there is nothing novel illustrated, described or claimed herein. It may be formed according to any well-known or approved construction as to its general shape, the materials used, the arrangement of compartments, etc. In practice the main body walls are composed partly of insulating material such as cork, and the doors are similarly insulated.

We are here chiefly concerned with that part of the refrigerator having means defining a compartment for ice, which means will be understood in the present instance as being the top wall 9, the upper portions of 40 the side walls 10, the door 12^a and the bottom wall 13 (Fig. 3) usually covered with a sheet of zinc 15. The pipe 16 leading from the downwardly-inclined wall or support 15 is for carrying away water from 45 the ice compartment.

The main refrigerator body illustrated may be considered one which originally was provided with a door at the rear end of the ice compartment in all material respects like 50 the door 12^a, and that such door was removed to provide a relatively large opening through the rear wall 11 having substantially the cross area of the ice compartment.

Rigid with the main body is an extension body having a top wall 20, a bottom wall 21, and two side walls 22, this extension body being rectangular in shape, open at both ends, and of such lateral and vertical dimensions that when normally applied to the rear wall 11 its hollow interior 24 will be in alignment with the hollow interior 14. Its walls have insulating material and may be formed in all respects after the general practice in making refrigerator bodies. It is

shown as being secured to the main body by four bolts or tie rods 25 extending through the main body and through the extension body. Several of these rods are shown complete partly by dotted lines in Figs. 2 and 70 3. A door 26 having a hinge and latch means which may be considered in all respects like those shown for the front door 12^a in Fig. 1 holds the sealing closure 26 in readily removable relation to the outer end 75 of the extension body.

This extension body will ordinarily have sufficient horizontal depth to pass through the wall of a building, indicated at 27 by dotted lines, whereby access may be had to 80 the hollow interior from the side of the wall opposite to that adjacent to which the main body of the refrigerator is placed.

The ice compartments of such refrigerators are usually lined with sheet metal such as zinc, and I have shown such lining 27 on the inner surface of the extension body walls. The bottom walls 21 of this extension body will preferably be formed with a downwardly and inwardly inclined slant so 90 that the lining 27 has this slant also and is thereby adapted to carry water to the drip pipe 16. It will be noted further that the lining 27 and 27^a extends materially beyond the walls of the extension body whereby by these extensions 27^b of the lining overlap portions of the means defining the inner surfaces of the main body thereat whereby leakage at the connection between the main body and the extension body is avoided. 100

As the device is illustrated, the extension body constitutes an attachment which may be applied to refrigerators now in use, and at very little expense. When the improved refrigerator is originally provided 105 with such an extension body it may be formed with walls common to both units or otherwise made as one body.

The hollow interior 24 constitutes at once a passageway for ice and an ice compartment, and forms with the compartment 14 a unitary compartment for ice. It will be noted that according to this improvement a relatively long cake of ice will be accommodated. For instance, if the left-to-right 115 width of the main body compartment be only such as to accommodate the width of a one-hundred-pound rectangular cake of ice, provision is thus made for the reception of such a cake, and thereby the capacity of 120 the refrigerator is increased from normally that of say a fifty-pound cake to a one-hundred-pound piece of the standard shape. In ordinary practice the fifty-pound piece would extend longitudinally with the door 12^a of Fig. 1, whereas with these improvements the end of a one-hundred-pound piece would be directed toward the door 12^a. This addition to the capacity results in various advantages including a reduction in the 130

number of fillings, the saving of expense to the ice merchant and of inconvenience to the user, and all with better refrigeration.

In this connection it may be pointed out that the most economical and most generally satisfactory merchandising and use of ice is in handling only pieces of standard sizes not less in weight than one hundred pounds each, and that the present improvements make such practice possible even with refrigerators of normally relatively small size; and in addition thereto the many objections to prior practices in outside icing are overcome.

15 The drawings herewith show a refrigerator having an ice compartment at the top. The invention may be embodied equally in such as have the ice compartment at a side or in some other location. In the various 20 constructions the extension body will be appropriately positioned to provide the desired results.

A valuable feature of the improvements is in the fact that the main body of the refrigerator is not enlarged, and that the present 25 advantages are had through the utilization of space outside the room in which the refrigerator is installed.

I contemplate as being included in these 30 improvements such changes and departures from what is herein specifically illustrated and described as fall within the scope of the appended claims.

I claim:

35 1. In a refrigerator, the combination of walls forming a hollow refrigerator main body, walls forming a hollow extension body rigid with and extending from the main body and opening thereinto, means in the 40 main body forming with the hollow interior of the extension body, a unitary ice compartment, and a closure for sealing the outer end of the extension body.

2. In a refrigerator, the combination of 45 walls forming a hollow refrigerator main body, walls forming a hollow extension body rigid with the main body, opening thereinto and extending therefrom a sufficient 50 distance to pass substantially through a building wall for the purposes specified, and means in the main body forming with the 55 hollow interior of the extension body a unitary ice compartment which includes a part of the hollow interior of the main body and the hollow interior of the extension body, and a readily removable closure for sealing the outer end of the extension body.

3. In a refrigerator, the combination of

walls forming a hollow main body having means defining an ice compartment therein, one of said body walls having a substantially large opening therethrough at said compartment, means forming a hollow open-ended extension body having a hollow interior, means holding said extension body rigid 65 with and in tight relation to said main body and in communication with the hollow interior thereof through said opening, the hollow interior of said extension body constituting a passageway and ice compartment open to said other compartment and forming therewith a unitary compartment for ice, and a closure for sealing the outer end of said extension body.

4. In a refrigerator, the combination of 70 walls forming a hollow main body having means defining an ice compartment therein, one of said body walls having a substantially large opening therethrough at said compartment, means forming a hollow open-ended extension body having heat-insulating 80 walls and having a hollow interior substantially the shape and size in cross view of said opening, said extension body having sufficient length to pass substantially 85 through a building wall for the purposes specified, means holding said extension body rigid with and in tight relation to said main body and in communication with the hollow interior thereof through said opening, the 90 hollow interior of said extension body constituting a passageway and ice compartment open to said other compartment and forming therewith a unitary compartment for ice, and a readily removable heat-insulating 95 closure for the outer end of said extension body.

5. In a refrigerator, the combination of 100 walls, including a vertical rear wall, forming a main body having means defining an ice compartment therein, said rear body wall having a substantially large opening therethrough at said compartment, means forming a hollow open-ended extension body 105 rigid with and in tight relation to said main body, opening thereinto through said opening, extending horizontally from the main body, and providing an extension of and an enlargement of said ice compartment, said extension body being adapted to enter an 110 opening in a building wall for access from the other side of such wall, and a readily removable closure for sealing the outer end of said extension.

OTTO STRUFE.
